TURBO COUPLING

Fritz Kugel, Heidenheim-on-the-Brenz, Germany,
assignor to American Voith Contact Company
Inc., New York, N. Y.

Application February 18, 1937, Serial No. 126,514
In Germany February 20, 1936

10 Claims. (Cl. 60—54)

This invention relates to fluid power transmitters, and in particular, to arrangements for filling and emptying such transmitters with respect to the working fluid.

5 One object of this invention is to provide a fluid power transmitter circuit having a working chamber and a fluid storage chamber, with oppositely facing stationary scoop tubes, one of which is adapted to empty the fluid storage 10 chamber and the other to fill it, these scoop tubes communicating with separate compartments in a fixed casing, from which communication is made with a fluid source, such as a fluid reservoir or tank.

15 Another object is to provide a fluid power transmitter circuit, as described above, wherein a control valve is arranged between the fluid power transmitter and the fluid source for selectively connecting one of the scoop tubes with 20 the fluid source while disconnecting the other scoop tube therefrom, this valve being arranged in an intermediate position to cut off communication with both of the scoop tubes so as to maintain the filling of the transmitter in a fixed 25 condition.

Another object is to provide a fluid power transmitter circuit, as described above, wherein the scoop tubes consist of a single U-shaped tube having an aperture at the lowest portion of the 30 tube, arranged to be immersed in a fluid in the storage chamber, and connected to serve either as a fluid intake or fluid delivery port, depending upon which arm of the U-shaped tube is connected with the fluid source.

35 Another object is to provide a fluid power transmitter circuit, as described above, wherein a by-pass line with a one-way valve permits circulation of the working fluid through the transmitter, yet prevents the return of the fluid into 40 the transmitter when the fluid contents of the transmitter are drained into the fluid source by suitably shifting the control valve.

In the drawings:

Figure 1 is a longitudinal section through one 45 embodiment of the fluid power transmitter circuit of this invention.

Figure 2 is a left-hand front elevation, partly in section, of the fluid power transmitter circuit shown in Figure 1.

50 Figure 3 is a front elevation of a modification of the fluid power transmitter circuit shown in Figures 1 and 2.

Figure 4 is another modified fluid power transmitter circuit for use with a fluid power transmitter, such as is shown in Figure 1, but employ-

ing a displacement body for control purposes.

Figure 5 is another modification, similar to Figure 4, but employing a movable inlet tube for varying the level at which the tube will draw in fluid from the fluid source.

5 Figure 6 is an enlarged view of the lower portion of the U-shaped scoop tube in Figure 3.

In general, the fluid power transmitter circuit of this invention consists of a fluid power transmitter with a rotatable casing having intercommunicating fluid storage and working chambers with driving and driven rotors in the working chamber, and a stationary casing having fluid intake and outlet compartments with oppositely facing scoop tubes in the storage chamber and 10 connected to the compartments for withdrawal of fluid from the intake compartment and for delivery of fluid to the outlet compartment.

15 Another feature of the invention consists in a single control valve adapted in opposite positions 20 to shut off communication between the fluid reservoir or fluid source and one of the scoop tubes, while opening communication between this reservoir or tank and the other scoop tube. Preferably, the control valve is also arranged to provide 25 an intermediate position in which both scoop tubes are shut off from communication with the fluid reservoir so as to maintain the filling of the transmitter in a fixed condition while the 30 valve is in this intermediate position.

Still another feature of the invention resides in the provision of a by-pass line extending between one of the scoop tube lines and the working chamber so as to permit the circulation of fluid 35 between the various chambers of the transmitter, yet having a spring-loaded valve to prevent the fluid from returning to the transmitter when the control valve is shifted to cause the outlet scoop tube to be connected to the reservoir to drain the fluid from the storage chamber into 40 the reservoir.

A modification of the invention consists of providing a single U-shaped scoop tube interconnecting the intake and outlet compartments of the stationary casing, and having a port at the 45 lowest portion of the tube, this port serving as a fluid delivery port while the fluid intake line is connected to the reservoir, and as a fluid withdrawal port while the fluid outlet line is connected to the reservoir.

Hitherto, suitable pumps have been employed to deliver the working fluid from the reservoir to the fluid power transmitter. The fluid which escaped by leakage from the transmitter during 50 operation was replenished by the pump, so that 55

the filling of the transmitter remained complete while the pump was in operation. When it was desired to empty the transmitter the pump was halted so that no more fluid was delivered to the transmitter, and the fluid within the transmitter was returned to the reservoir through a stationary scoop tube, or other suitable means. This arrangement, however, had the disadvantage that the filling pump absorbed a considerable amount of power, and resulted in an increased cost of installation or operation, or both. In such an arrangement, moreover, the filling pump was required to be of large capacity in order to fill the transmitter quickly when filling became necessary.

In order to maintain the transmitter in a filled condition, moreover, an additional leakage pump which absorbed less power was usually employed. Even when the filling pump was dispensed with by employing an overhead tank and gravity delivery of fluid, it was usually necessary to provide a leakage pump in order to deliver the leakage fluid from the lowest point of the fluid circuit to the overhead tank.

Referring to the drawings in detail, Figure 1 shows a fluid power transmitter having an impeller *c* mounted on a driving shaft *c*₁ and a runner *d* mounted on a driven shaft *d*₁. A casing consisting of shells *c*₂, *c*₃ and *c*₆ is connected to the impeller *c* so as to rotate therewith. The shells *c*₂ and *c*₃ provide an oil chamber *c*₄, into which the oppositely facing stationary scoop tubes *a* and *b* project in such a manner that their mouths are immersed in the fluid within the peripheral portion of the oil chamber *c*₄. The scoop tube *a* and scoop tube *b* are connected, respectively, to chambers *q* and *r* formed in a stationary casing *p* by means of the partitions *p*₁, *p*₂ and *p*₃.

The scoop tube *a* has its offset scoop portion immersed in the fluid in the oil chamber *c*₄ for the purpose of directing the fluid from the chamber *c*₄ to the chamber *q*, and thence through the conduit *a*₁, valve *e* and conduit *e*₁ to the tank *f*. The scoop tube *b*, on the other hand, has its offset scoop portion immersed in the oil chamber *c*₄ in the opposite direction to the offset scoop portion of the scoop tube *a* for the purpose of creating a suction so as to draw fluid through the conduit *e*₁, the valve *e* and the conduit *b*₁, into the chamber *r*, and thence through the scoop tube *b*, into the oil chamber or storage chamber *c*₄.

The valve *e* is arranged in an intermediate position to cut off communication between both of the conduits *a*₁ and *b*₁ and the conduit *e*₁, and is held in this intermediate position by springs *e*₃ and *e*₄. When the valve *e* is in this intermediate position it maintains the filling of the fluid power transmitter in a constant condition. When the hand lever *e*₂, which controls the valve *e*, is moved to the left, the scoop tube *b* is connected to the oil tank *f*, whereby oil is drawn into the oil storage chamber *c*₄. On the other hand, when the hand lever *e*₂ is moved toward the right, the scoop tube *a* is connected to the oil tank *f* through the valve *e*, and the conduits *e*₁ and *a*₁, so that the oil is withdrawn from the storage chamber *c*₄ into the oil tank *f*.

A filler cap *c*₅ is provided in the top of the casing shell *c*₃ for the introduction of a sufficient quantity of oil into the storage chamber *c*₄, in order to initiate the suction effect of the scoop tube *b*. It will be seen from Figure 1 that when the casing *c*₃ *c*₂ *c*₆ rotates with the driving shaft

*c*₁, the oil therein forms an oil ring in the peripheral portion thereof under the influence of centrifugal force.

Extending between the remaining chamber *s* in the stationary casing *p* and the conduit *a*₁ is a by-pass conduit *g* with a spring-loaded valve *g*₁. This arrangement serves during operation to circulate that part of the working fluid which passes from the chamber *s* of the stationary casing *p*, through the holes *n*, into the working chamber *t* lying between the shells *c*₂ and *c*₆. From the working chamber *t* the fluid passes through holes *m*, into the storage chamber *c*₄, whence it is recirculated by the scoop tube *a*, the conduit *a*₁ and the by-pass line *g* by way of the spring-loaded valve *g*₁. When the fluid is drained from the transmitter by connecting the scoop tube *a* with the tank *f*, the spring-loaded valve *g*₁ prevents the fluid from returning into the transmitter.

The modification shown in Figure 3 is similar to the fluid power transmitter shown in Figures 1 and 2, except that a single U-shaped scoop tube *h* is provided in place of the two separate scoop tubes *a* and *b*. This U-shaped scoop tube *h* at its lowest point has a port *h*₁, through which the fluid passes into or out of the storage chamber *c*₄, depending upon which arm of the U-shaped scoop tube *h* is connected with the conduit *e*₁ and tank *f* by means of the control valve *e*. When the left-hand arm of the U-shaped scoop tube *h* is so connected, fluid is drawn from the tank, through the valve *e* and conduit *b*₁, into the chamber *r* and thence passes downwardly through the port *h*₁, into the storage chamber *c*₄. On the other hand, if the right-hand arm of the U-shaped scoop tube *h* is connected with the conduit *e*₁ by means of the control valve *e*, the fluid in the storage chamber *c*₄ is withdrawn therefrom through the port *h*₁, into the chamber *q*, whence it passes through the conduit *a*₁, the control valve *e* and the conduit *e*₁, into the tank *f*.

The modification shown in Figure 4 includes a fluid power transmitter similar to that previously described, but having a displacement body *i* suspended from a cable wound upon the drum *k*. By raising and lowering the body *i* the level *xy* of the fluid in the tank *f* can be varied so that the mouth of the filling conduit *b*₁ will be exposed when the fluid level drops in response to the lifting of the displacement body *i* out of the tank *f*. When the fluid power transmitter is to be completely or partially filled, however, the displacement body *i* is lowered into the tank *f*, causing the fluid level *xy* to rise to or above the mouth of the conduit *b*₁. In this modification the conduit *a*₁ extends nearly to the bottom of the tank *f*, and contains a throttle valve *l* arranged to prevent too much fluid from returning to the tank *f* during normal operation.

The modification shown in Figure 5 serves a similar purpose to the circuit shown in Figure 4, but provides an adjustably movable conduit *b*₂ in place of the displacement body *i*. By raising or lowering the adjustable conduit *b*₂ by means of the rod *b*₃, the level at which the mouth of the conduit *b*₂ ceases to draw in fluid from the tank *f* can be suitably varied. The movable conduit *b*₂ is mounted so as to telescope within the conduit *b*₄, and a packing prevents leakage therebetween. In place of the movable conduit *b*₂ a flexible tube immersed in the fluid tank can be employed. The depth of immersion thereof can be adjusted.

5 by raising or lowering the mouth of this tube. It will be understood that the control valve *e*, displacement body *i* or movable conduit *b*, may be moved by hand, by governor or by other suitable means, without departing from the scope of the invention.

10 If it is desired to use the fluid power transmitter for both directions of rotation without a special change-over device, a second by-pass conduit *g*, and spring-loaded valve *g*, are provided for interconnecting the chambers with the conduit *b*. The operation of this second by-pass conduit and valve is similar to that of the first by-pass conduit *g* and valve *g*, previously described. The 15 operation of the various forms of the invention has been sufficiently described in connection with the construction thereof, and requires no additional explanation.

20 It will be understood that I desire to comprehend within my invention such modifications as come within the scope of the claims and the invention.

25 Having thus fully described my invention, what I claim as new and desire to secure by Letters Patent, is:

30 1. In a fluid power transmitter, a rotatable casing having intercommunicating fluid storage and working chambers, a driving rotor and a driven rotor in said working chamber, a stationary casing having a centrally disposed hub-like portion with fluid intake and outlet compartments therein, stationary scoop tube means having oppositely facing mouths in said storage chamber, said scoop tube means extending inwardly to said hub-like portion and connected 35 respectively for withdrawal of fluid from said intake compartment and for delivery of fluid to said outlet compartment, a fluid source, means for connecting said fluid source with said intake and outlet compartments respectively, and a valve in said connecting means for selectively placing said fluid source in communication with one of said compartments, said storage compartment being adapted to contain a liquid the level 40 of which is above the level of said mouths at all times.

45 2. In a fluid power transmitter, a rotatable casing having intercommunicating fluid storage and working chambers, a driving rotor and a driven rotor in said working chamber, a stationary casing having fluid intake and outlet compartments, stationary scoop tube means having oppositely facing mouths in said storage chamber connected respectively for withdrawal of fluid 50 from said intake compartment and for delivery of fluid to said outlet compartment, a fluid source, means for connecting said fluid source with said intake and outlet compartments respectively, and a valve in said connecting means for selectively placing said fluid source in communication with one of said compartments while cutting off communication with the other of said compartments.

55 3. In a fluid power transmitter, a rotatable casing having intercommunicating fluid storage and working chambers, a driving rotor and a driven rotor in said working chamber, a stationary casing having fluid intake and outlet compartments, stationary scoop tube means having oppositely facing mouths in said storage chamber connected respectively for withdrawal of fluid 60 from said intake compartment and for delivery of fluid to said outlet compartment, a fluid source, means for connecting said fluid source with said intake and outlet compartments re-

spectively, and a valve in said connecting means for selectively placing said fluid source in communication with one of said compartments while cutting off communication with the other of said compartments, said valve being adapted in a 5 neutral position to cut off communication between said source and both of said compartments, whereby to maintain the filling of said fluid power transmitter in a constant condition.

10 4. In a fluid power transmitter, a rotatable casing having intercommunicating fluid storage and working chambers, a driving rotor and a driven rotor in said working chamber, a stationary casing having a centrally disposed hub-like portion with fluid intake and outlet compartments therein, and stationary intake and outlet scoop tubes extending inwardly to said hub-like portion and connected respectively to said intake and outlet compartments and having oppositely directed scoop portions adapted respectively for conduction of fluid from said intake compartment to said storage chamber and for delivery of fluid from said storage chamber to said outlet compartment, the oppositely directed portion of said outlet scoop tube having an opening 20 which opening is below the level of the liquid at 25 which opening is below the level of the liquid at all times in said storage chamber.

30 5. In a fluid power transmitter, a rotatable casing having intercommunicating fluid storage and working chambers, a driving rotor and a driven rotor in said working chamber, a stationary casing having fluid intake and outlet compartments, and a U-shaped stationary scoop tube interconnecting said intake and outlet compartments and having an intermediate port immersed 35 in the fluid in said storage chamber.

40 6. In a fluid power transmitter, a rotatable casing having intercommunicating fluid storage and working chambers, a driving rotor and a driven rotor in said working chamber, a stationary casing having fluid intake and outlet compartments, stationary scoop tube means having oppositely facing mouths in said storage chamber connected respectively for withdrawal of fluid from said intake compartment and for delivery 45 of fluid to said outlet compartment, a fluid source, intake and outlet conduits for connecting said fluid source with said intake and outlet compartments respectively, a by-pass conduit connected to provide intercommunication between 50 said working chamber and said outlet conduit, and means for regulating the passage of fluid through said by-pass conduit.

55 7. In a fluid power transmitter, a rotatable casing having intercommunicating fluid storage and working chambers, a driving rotor and a driven rotor in said working chamber, a stationary casing having fluid intake and outlet compartments, stationary scoop tube means having oppositely facing mouths in said storage chamber connected respectively for withdrawal of fluid 60 from said intake compartment and for delivery of fluid to said outlet compartment, a fluid source, intake and outlet conduits for connecting said fluid source with said intake and outlet compartments respectively, a by-pass conduit connected to provide intercommunication between 65 said working chamber and said outlet conduit, and a yieldingly urged valve for regulating the passage of fluid through said by-pass 70 conduit.

75 8. In a fluid power transmitter, a rotatable casing having intercommunicating fluid storage and working chambers, a driving rotor and a driven rotor in said working chamber, a sta-

- tionary casing having fluid intake and outlet compartments, stationary scoop tube means having oppositely facing mouths in said storage chamber connected respectively for withdrawal 5 of fluid from said intake compartment and for delivery of fluid to said outlet compartment, a fluid source, means for connecting said fluid source with said intake and outlet compartments respectively, a valve in said connecting means 10 for selectively placing said fluid source in communication with one of said compartments while cutting off communication with the other of said compartments, said valve being adapted in a neutral position to cut off communication between 15 said source and both of said compartments, whereby to maintain the filling of said fluid power transmitter in a constant condition, and means tending normally to urge said valve into said neutral position.
- 20 9. In a fluid power transmitter, a rotatable casing having intercommunicating fluid storage and working chambers, a driving rotor and a driven rotor in said working chamber, a stationary casing having fluid intake and outlet compartments, stationary scoop tube means having oppositely facing mouths in said storage chamber 25

connected respectively for withdrawal of fluid from said intake compartment and for delivery of fluid to said outlet compartment, a fluid source, intake and outlet conduits for connecting said fluid source with said intake and outlet compartments respectively, a by-pass conduit connected to provide intercommunication between 5 said working chamber and each of said intake and outlet conduits, and a yieldingly urged valve for regulating the passage of fluid through 10 each by-pass conduit.

10. In a fluid power transmitter, a rotatable casing having intercommunicating fluid storage and working chambers, a driving rotor and a driven rotor in said working chamber, a stationary 15 casing having fluid intake and outlet compartments, and stationary scoop tube means having oppositely facing inlet and outlet openings, the outlet opening of said scoop tube means being below the liquid level at all times of the 20 liquid within said storage chamber whereby when said storage chamber is rotating said liquid may be replenished by suction created within said outlet tube.

25

FRITZ KUGEL.
